UNITED STATES PATENT OFFICE

151,796

DESIGN FOR AN AUTOMOBILE

George C. Sullivan, Hollywood, Calif.

Application February 10, 1947, Serial No. 136,808

Term of patent 14 years

(Cl. D14—3)

To all whom it may concern:

Be it known that I, George C. Sullivan, a citizen of the United States, residing at Hollywood, in the county of Los Angeles and State of California, have invented a new, original, and ornamental Design for an Automobile, of which the following is a specification, reference being had to the accompanying drawings, forming a part thereof.

Figure 1 is a perspective view of an automobile embodying my new design;

Figure 2 is a side elevation thereof;

Figure 3 is a top view thereof; and

Figure 4 is a front elevation of the automobile.

I claim:

The ornamental design for an automobile, substantially as shown.

GEORGE C. SULLIVAN.
